2 Sheets-Sheet 2

UNITED STATES PATENT OFFICE.

WILLIAM EDWIN CAMPBELL, OF SYDNEY, NEW SOUTH WALES, AUSTRALIA.

CONE WINDER.

Application filed January 6, 1922. Serial No. 527,418.

To all whom it may concern:

Be it known that I, WILLIAM EDWIN CAMPBELL, a subject of the King of Great Britain and Ireland, residing at Sydney, 5 New South Wales, Australia, have invented certain new and useful Improvements in Cone Winders, of which the following is a specification.

This invention relates to cone winders in which yarns are wound in filling wind on knitting or winder bobbins from skeins or cops or jack bobbins. It consists in an improved builder motion in which the flow of yarn to the winder bobbin is stepped up 10 at the beginning of each rise of the building motion by tappet mechanism actuated by the vertical oscillation of the ring rail and coasting through an automatic clutch with a spline collar to rotate a key grooved 15 lead screw mast which carries the yarn quirl.

Each spindle in the assembly is independent of the others and each bobbin may be removed and set without arresting the operation of the other winders in the assembly. 20 The structure and operation of the individual winders making up an assembly being identical, it is sufficient that the description which follows describes a single winder 25 element.

A bracket fixed to the ring rail carries a vertical guide post fixed to it, and also carries a lead screw threaded vertical mast which is contained in a key sleeve which is 30 provided with automatic pawl clutch mechanism and a tappet action operating arm. A claw is carried on the bracket and engages the thread on the mast. As the mast is rotated by means of the clutch and key 35 sleeve mechanism, it is moved upwardly over the traversing claw. A looped wire guide fixed on a head moved by the mast leads the yarn to the bobbin and determines the yarn traverse on the bobbin. The tappet 40 operating arm takes a stroke at every bottom throw of the ring frame by making contact with the table or a striker. The clutch is provided with a gravity release lock which is opened when the tension on 45 the yarn is lost, as when a break occurs; the building motion is then immediately arrested as the key sleeve is then no longer operative for rotating the mast. The mast is reset at bottom position by releasing the 50 traversing claw, and thus allowing the

mast to slip down through the sleeve by gravity.

In the accompanying drawing:—

Fig. 1 is a top plan;

Fig. 2 is a side elevational view;

Fig. 3 is a transverse sectional elevation on the plane 3—3, Fig. 1;

Fig. 4 is a sectional elevation of the mast traversing mechanism; and

Fig. 5 is a top plan of the detent clutch 65 associated with the mast sleeve.

The winder bobbin 10 is mounted in the usual manner on the head of the winder spindle 11, a whorl (not shown) being fitted on the lower portion of this spindle 70 for the purpose of applying rotation to it, according to usual practice.

The angle-iron rail 12 is carried by slide members 13 to which vertical oscillating motion is applied by means of a heart cam 75 mechanism, the cam having one operating face longer than the other so that quick motion is applied to the rail in one direction and relatively slow motion in the opposite direction, the quick motion being provided 80 to lay the yarn close on the bobbin, and the slow motion to bind the yarn from nose to shoulder, and in an overlay from shoulder to nose.

14 is a bracket fixed to the angle-iron 85 rail 12. Midway of its length it carries a fixed guide post 15 of rectangular section, and this guide post carries upon it a sleeve 16 which is a neat slide fit. A bracket 17 from the sleeve 16 carries a looped yarn 90 guide 18, and also carries the top end 20 of a screwed mast 21 in a head bearing 19.

The mast 21 is key slotted longitudinally as shown at 52 and a clearance 53 is provided for it in the table 54. At its outer 95 end the angle-iron rail bracket 14 is terminated in a collar bearing 22. Within this collar bearing a tubular sleeve 23 is rotatably fitted, said sleeve having a bearing collar 24 at its top end and locked against longitudinal movement at its lower end by a spring ring 25. A helical groove 58 in the sleeve 26 is engaged by stub ends 27 of screws 28 fixed in the tappet arm 29; this arm is mounted for movement in a vertical direction on pivot pins 30 fixed in the boss 31 on the under side of the bracket 14. 49 is a stay bracket from the boss 31 supporting the lead screw mast 21 in vertical position. 32 is a tappet head screw fitted in the 110

outer end of the tappet arm 29 and provided with a locking nut 33; this screw 32 is arranged to contact with the striker plate 34 on the table 54 when the ring rail motion is at bottom throw; the top end of the sleeve 26 is formed as a crown detent 35 engageable with the complementary crown detented floating ring 36. 37 are pin bolts slidably mounted in the top end of the sleeve 23; the top ends of these bolts 37 are fixed in a collar 38; this collar is engaged by the claw jaw 39 of the counterweight trip arm 40. The thread of the yarn 50 is carried through the mouth 41 of the counterweight 42 on the outer end of the arm 40 and thence through the looped guide 18. As the yarn is under tension the arm 40 is sustained and the floating collar 38 is depressed with the result that the bolts 37 are engaged in recesses 60 in the floating ring collar 36. 48 is a spline key fixed in the sleeve 23 and working freely in the longitudinal slot 52 in the lead screw mast. 44 is a spring claw fixed to the end of the bracket 14 and engaging the threads on the screw mast 21. The face of the claw 44 is shaped and finished complementarily to the surface of the lead screw in order to minimize friction and wear.

45 is a finger piece by means of which the spring claw 44 may be disengaged from the screwed spindle 21 to allow said spindle to drop by gravity to bottom or starting position. 51 is a ring bearing supporting the floating ring 36.

The operation is as follows:—

The lead of yarn from a skein or cop or jack bobbin being laid through the mouth 41 of the counterweight 42 and thence through the curl of the guide 18 is laid onto the lower part of the bobbin 10 in the usual way for starting up. At this position the lead screw mast 21 is at bottom position, the claw 44 having been released manually by pressing the finger piece 45. As the rail 12 carrying with it the bracket 14, performs a vertical oscillating movement the tappet 32 at bottom stroke contacts with the striker plate 34 on the table 54; at each contact the feather pins 27, running up the helical grooves 58 apply a partial rotation to the sleeve 26. In the lifting movement rotation of the sleeve 26 is reversed. During the positive movement of the sleeve 26, the detent teeth 35 are engaged with the detent teeth on the floating ring 36 which is locked by the slide bolts 37 to the sleeve 23. As owing to the tension on the yarn the counterweight lever 40 is lifted, the collar 38 carrying the bolts 37 is pushed downward; the result is that partial rotation is applied to the sleeve 23, and by means of the spline key 48 this partial rotation is applied to the lead screw mast 21. As the claw 44 is engaged with the threads of the mast this ro-

tative movement has the effect of causing the mast to climb to a pre-determined distance, which is proportioned to the speed of rotation of the spindle 11, so that the necessary close lay of the yarn on the bobbin is obtained. In the upward movement of the angle-iron rail 12 the tappet arm 29 drops, and in the reverse movement of the sleeve 26 then produced, the detent teeth 35 ride freely over the mating detent teeth on the floating ring 36, sufficient clearance being allowed for this purpose. Step-by-step upward climb of the mast continues at every oscillation of the rail 12. The binding lay for securing the close laid lay is run on during the downward movement of the looped guide 18 and the angle-iron rail movement. If the yarn should break, the weight 42 being no longer sustained by its tension, drops to the position shown in Fig. 3, and in dropping lifts the collar 38, and the bolts 37 being thus freed, the sleeve 23 is disengaged from the floating detent ring 36 and climbing movement is no longer applied to the mast 21 and the looped guide 18 remains in the position which it occupied at the moment the break in the yarn occurred.

The degree of rotation applied to the screwed mast at each oscillation of the ring frame is variable by adjustment of the tap-pet head screw 32.

What I claim as my invention and desire to secure by Letters Patent is:—

1. In a cone winder, a building motion for effecting a traverse of the yarn including an angle-iron rail, a bracket thereon, a guide post on said bracket, a non-rotatable arm slidable on the guide post, a looped guide mounted on said arm, a vertically disposed rotatable screwed mast suspended from the non-rotated arm and disposed through the outer end of the bracket on the angle-iron rail, a collar mounted in said bracket and splined to the mast, a retractable claw fixed on said bracket engageable with the mast, a helically slotted sleeve clutched to said collar and a tapped arm hung on said bracket coacting with the helically slotted sleeve to effect partial rotation of the collar once in each oscillation of the angle-iron rail.

2. In a cone winder, in combination with a vertical oscillating angle-iron rail, a looped guide to effect traverse of yarn on the bobbin, a vertically disposed lead screw associated with the looped guide and means for applying intermittent rotation to said screw including a tapped and a clutch operatively associated with and dependent on the vertical oscillation of the angle-iron rail for raising the looped guide.

3. A cone winder comprising a bobbin spindle, an angle-iron rail, a bracket on said rail, a guide post on the bracket, a non-rotating arm slidable on the post, a lead

- screw connected with the outer end of the arm and disposed through the outer part of the bracket, a tubular sleeve rotatably mounted in said bracket, a spline for connecting the sleeve to the screw, a second sleeve rotatable about the tubular sleeve and provided with a helical groove, a clutch for effecting engagement between the sleeves and a tappet arm hung from the bracket
- 5 dependent for movement on the oscillation of the angle-iron rail and acting through the helical groove to apply rotation of movement to the lead screw.
4. In a cone winder as claimed in claim
- 15 3, a counterpart clutch member having crown teeth engageable with the helically grooved sleeve and rotatable about the tubular sleeve and a locking device for effecting engagement of the clutch member with the
- 20 tubular sleeve including a gravity releasing

member which is sustained by the yarn whilst in tension between the looped guide and the bobbin.

5. A cone winder including an oscillatory rail, a bracket carried thereby, a vertical guide post on the bracket, an arm slidable on the guide post, a looped guide carried by the arm, a lead screw connected with the arm on the guide post, a retractable claw on the bracket for engaging the screw, a helically grooved sleeve associated with the bracket and the screw, a one-way toothed clutch between the sleeve and the screw and a tappet arm hung from the bracket and movable at each oscillation of the angle-iron rail and associated with the helically grooved sleeve to effect partial rotation of the lead screw.

In testimony whereof I affix my signature.

WILLIAM EDWIN CAMPBELL.
